UNITED STATES PATENT OFFICE

1,928,441

INNER PARTITION FOR BURGLARPROOF CHEST

Charles F. Sjoberg, York, Pa., assignor to York Safe & Lock Company, York, Pa., a corporation of Delaware

Application September 9, 1932. Serial No. 632,334

9 Claims. (Cl. 109—1)

The holdup problem has become so serious in connection with moving picture houses and chain stores that there is a general demand for the provision in connection with all burglarproof 5 chests, of means providing for the immediate deposit of the cash as received so that it becomes inaccessible to the clerk or cashier. In this way any attempt to hold the clerk or cashier up and obtain delivery of the cash is made ineffective. 10 The immediate deposit of the cash so it cannot be withdrawn also reduces or prevents thefts by employees.

A great many moving picture houses and chain 15 store managements were provided with burglar-proof chests before this demand arose, the old practice being to accumulate the cash in a cash register or till and to place it in the chest at the end of a business day, or even to put it in the chest from time to time, the door being closed 20 and locked at night only. This made it necessary for the cashier to have access to the chest.

Under these circumstances, many successful 25 holdups occurred as it was only necessary to intimidate the clerk to cause him to deliver whatever cash was accessible to hand which, in many instances, would be a considerable amount.

The necessity for immediate deposit of the cash 30 so that it is inaccessible to the clerk as well as to the holdup man, has been met as to a new type of chest by the provision of an inner partition which is slotted to admit packages or other deposits of cash as received or accumulated to whatever extent is desired by the cashier, the partition having a door which is locked independently of the combination lock of the outer door. This lock 35 is usually under the control of a trusted employee or officer of the owner organization who is provided with a key or is acquainted with the combination if a combination is used, the inner compartment formed by the partition being ordinarily not accessible to the employee who receives or 40 deposits the cash therein.

The applicant does not claim to be the inventor 45 of the inner partition with the slot and door as described above, as such partitions have been in use for many years. However, the installation of such a partition has in accordance with the previous practice, involved the provision either of a partition cast solid with the outer casing 50 which is not feasible after the chest is completed, or the use of screw fastenings to which the boring and tapping of holes within the chest is incident.

55 The problem which has been solved by the present invention has arisen on account of the fact

that numerous organizations have already installed chests of modern design without inner partitions. The provision of such a partition properly secured in a chest already in use has involved the drilling and tapping of holes and fitting of 60 parts in the field which could only be accomplished at considerable expense to the owner of the chest. The invention relates to a solution of this problem whereby the bulk of the labor incident to field installation of these partitions is 65 eliminated, the partition being quickly and easily installed and so secured that its removal without first opening the door contained in the partition which gives free access to the deposits, is practically impossible.

In the accompanying drawings I have illustrated a chest equipped with a partition adapted to be secured and installed in accordance with the invention, together with the securing means which are a feature of the invention.

In the drawings:

Figure 1 is a front elevation of a chest equipped with a partition installed in accordance with the invention, the chest door being removed for convenience of illustration.

Figure 2 is a longitudinal vertical section on the line 2, 2 in Figure 1.

Figure 3 is a horizontal section on the line 3, 3 in Figure 1.

Figure 4 is an elevation of the left hand section of the partition looking at the same from the front of the chest, i. e., from the door opening.

Figure 5 is an elevation taken from the right in Figure 4 looking at the half of the partition shown in Figure 4 from the right in said figure.

Figure 6 is an elevation of the half of the partition which is on the right as seen from the chest door opening.

Referring to the drawings by numerals, each of which is used to indicate the same or similar parts in the different figures, the illustration includes a burglarproof chest 1, which in the form shown has a circular door opening 2 at the front closed by a circular rotary door 3 which may be of the type described in my previous Patent No. 1,850,639, issued Mar. 22, 1932, or of any suitable type, the form and construction of the door and door opening not being material to the invention except for the fact that in the form of chest shown the circular door opening leaves corner portions of the front wall of the chest at 4, 5, etc. which provide convenient forward supports for the inner partition 6 to be more fully described.

The inner wall 6, which with the means for supporting it is the important feature of the inven-

70

75

80

110

tion, is best illustrated in Figures 4, 5 and 6. As shown, this partition is formed in two sections 7 at the left and 8 at the right. In this instance, the section 8 is of slightly greater horizontal dimension than the section 7 which is to compensate for the fact that the chest as shown in Figure 1 has the circular door opening 2 slightly to the left of the center, the chest being substantially square in transverse cross section but of a horizontal width a little greater than its height. The transverse partition also has a circular door opening 9 which is preferably placed in axial alignment with the circular door opening 2, the line of division between the sections indicated by reference character 10 being most conveniently vertical and aligned with the center of this door opening which explains the fact that in the form shown the section 8 at the right is of slightly greater horizontal dimension than the section 7 at the left.

The partition 6 is shown as provided with a slot 11 at the top, one half of which is in each section 7 and 8. The halves are indicated as 11' and 11''.

The sections 7 and 8 are held in their assembled relation to each other to form a complete partition by means of a frame 12 which may be in the form of a ring or any other suitable shape, preferably conforming to the shape of the door opening 9. In this instance the ring 12 is concentric with the door opening and of slightly smaller inside diameter whereby it extends inwardly from the edge 15 of the door opening and provides a support at the back of the door 16 as best shown in Figure 2.

The frame or ring 12 is secured to the back of the partition 6 in any suitable manner as by means of patch bolts 14 shown in dotted lines in Figures 1 and 2. To receive these, the two sections of the partition are bored and tapped at 17 and the ring or frame 12 is countersunk as indicated at 18. In accordance with the well known practice, the patch bolts are made with a portion of the head removable and this portion is twisted off when the bolts are finally seated, but this does not occur until the partition has been assembled inside the chest in a manner to be described. The holes 17 are formed in both sections 7 and 8, and the countersunk holes 18 are made to register with them or vice versa.

The slot 11 in the partition is provided at the rear with a baffle 20 consisting of upper and lower inclined plates 21 and 22, having flanges 24 and 25, the flanges being preferably secured to the left hand section 7 of the partition, one above and the other below the slot in any suitable manner as by means of screws or rivets 26. The slot 11 being preferably formed in the two halves of the partition as shown in Figures 4 and 6, the two halves of the slot 11' and 11'' are brought into registration when the partition is assembled.

The partition is supported at the front by suitable means as hexagonal or other studs 28 which project forwardly from the partition, being preferably of angular cross section, so that they can be conveniently engaged by a wrench. These studs are shown, as pointed at their forward ends 29, where they bear against the inside of the front wall of the chest. The corner segments 4 and 5 beside the door opening are very convenient for this purpose, the studs 28, as shown being pointed at 29, are supported at their centers on the front wall segments 4 and 5 without the necessity for accurate finishing of contact-

ing surfaces which would be involved if they were flat. The studs 28 are preferably secured to the partition 6 by means of threaded shanks 30 which engage the threaded holes 31 in the partition and also project through and beyond the partition as indicated at 32.

At the rear the partition 6 is supported by suitable means preferably as follows: The projecting ends 32 are engaged by threaded sleeve nuts 33 which are preferably of hexagonal or other suitable angular cross section as viewed externally. These sleeves 33 are threaded to engage and are engaged with the projecting threaded ends 32 which are considerably shorter than the sleeves. Threaded into the outer end of each sleeve is a hexagonal pin or stud 34 having one end threaded to engage the threaded aperture 35 within the corresponding sleeve 33, and the stud or pin 34 is provided with a lock nut 36 threaded thereon to lock the sleeve 33 and the stud 34 in their assembled relation as finally adjusted to support the partition in the desired position or in the position which is determined by the length of the studs 28. Pins 34 are preferably pointed at 34'.

The manner of assembling the partition within the chest is of interest as the utility of the invention is dependent largely on the fact that this partition can be quickly and easily installed in the field and thus installed it serves all the purposes of a partition which is cast integrally with the outer casing or provided with a screw fastening by which it is attached to the walls of the chest. To assemble the partition within the chest, the sections 7 and 8 are first inserted through the door opening 2, and their inner edges including 36' and 36'' are brought in contact, the sections 11' and 11'' of the slot 11 being in registration. The ring or frame 12 is secured to the back of one half of the partition 110 when inserted, the partition being, in fact, ordinarily shipped with the two halves secured together by the ring, the bolts securing one section being removed when the sections of the partition are inserted through the door opening 2 120 as already described. The half of the partition with the ring attached is placed in upright position on the left side of the chest body, the ring being preferably permanently secured to the left side of the partition as seen from the door opening. The other half of the partition is then butted tight against it, the parts being located by means of the slot sections 11' and 11'', as already stated. The three bolts, 14' are then inserted through the counter-sunk holes 18 into 130 the right side of the partition and tightened.

The four studs 28 are then secured to the front of the partition, the threaded shanks 30 being inserted in the threaded holes 31 and tightened by means of a wrench engaging the hexagonal cross section of the stud 28. The pins 34 with the locknuts 36 thereon have already been screwed into the threaded hexagonal sleeves 33 being inserted well beyond the final assembled position. These sleeves 33 are then engaged with the projecting ends 32 of the threaded shanks 30 of the studs 28, and the sleeves are tightened against the surface of the partition. The pins 34 are now screwed back against the rear wall 37 of the chest forcing the points 29 of the studs 28 into close contact with the segments 4, 5 of the front wall of the safe at the sides of the door. When the pins 34 have been suitably tightened, the locknuts 36 are turned up against the corresponding ends 145 of the sleeves 33 after which the removable por-

tions of the heads of the patch bolts 14 are twisted off by means of a special wrench provided for this purpose.

The door opening 9 in the partition is closed by a door 38, Figure 1 which bears against the inner projecting portion of ring 12 and is held by means of a suitable lock 39 having a bolt 40 which projects over the frame or ring 12 on the opposite side to the side thereof engaged by the door, the opposite edge of the door being held by lug 41, which also projects over the ring or frame 12 and the door is supported in open position by a hinge 42, all of which details are not important. The invention relates to the improved form of sectional partition and the supporting means whereby the partition is assembled or secured within the chest with the minimum of expenditure of time and effort, the operation being easily accomplished in the field converting a plain chest into one which is the equal in every way to one having the partition formed integrally with the walls of the chest.

I have thus described specifically and in detail an inner partition for a burglarproof chest and the manner of assembling and securing the same in the field, the description being specific and in detail in order that the manner of constructing, applying, operating and using the invention may be fully understood, however, the specific terms herein are used descriptively rather than in a limiting sense, the scope of the invention being defined in the claims.

What I claim as new and desire to secure by Letters Patent is:

35. 1. In a burglarproof chest having a door opening, an inner partition made in a plurality of sections to be inserted through the door, means for securing the sections together after they are inserted to close the cross section of the chest substantially parallel to the plane of the door opening whereby the chest is divided into a plurality of compartments, and means secured to the partition and extending forwardly and rearwardly therefrom engaging the front and rear walls of the chest respectively, whereby the assembled partition is held in position in the chest dividing it into a front and rear compartment, the partition having a door opening with a door and a slot providing for the insertion in the inner compartment of articles to be stored.

2. In a burglarproof chest having a door opening, an inner partition made in a plurality of sections to be inserted through the door, means for securing the sections together after they are inserted to close the cross section of the chest substantially parallel to the plane of the door opening whereby the chest is divided into a plurality of compartments, and means secured to the partition and extending forwardly and rearwardly therefrom engaging the front and rear walls of the chest respectively, whereby the assembled partition is held in position in the chest dividing it into a front and rear compartment, the partition having a door opening with a door and a slot providing for the insertion in the inner compartment of articles to be stored, said means having an adjustment at the rear of the partition accessible through the door opening whereby the partition is accurately positioned and rigidly secured within the chest.

3. In a burglarproof chest, an inner partition having a door and a door opening therein, the partition dividing the chest into two compartments and consisting of a plurality of sections adapted for insertion through the chest door and

means for securing the sections together in their assembled relation the partition dividing the safe into a front and rear compartment, a chute leading from the front to the rear compartment, and a door in the partition beneath the chute both being accessible from the door of the chest.

4. The combination in a burglarproof chest having a door opening and wall portions parallel to the plane of the door opening of a removable partition having a slot and a door opening, the partition being made in a plurality of sections adapted for insertion through the door opening, means for securing the sections together within the chest and securing means for the partition engaging wall portions parallel to the door opening for supporting the partition within the chest to divide the chest into a plurality of compartments, the slot being adapted to admit the articles to be stored to the inner compartment.

5. The combination in a burglarproof chest having a front door and a door opening of a partition having a door, a door opening and a slot for the quick insertion of articles to be stored, the partition being in a plurality of sections to be inserted through the door opening, means for connecting the sections together in assembling the partition, and means accessible for removal only through the door opening in the partition for supporting the partition in the position in the chest to divide it into an inner and outer compartment.

6. The combination in a burglarproof chest having a front door and a door opening of a partition having a door, a door opening and a slot for the quick insertion of articles to be stored, the partition being in a plurality of sections to be inserted through the door opening, means for connecting the sections together in assembling the partition, and means accessible for removal only through the door opening in the partition for supporting the partition in the position in the chest to divide it into an inner and outer compartment, 100 said means comprising a member extending forwardly from the partition and engaging supporting means within the chest, said member having a shank extending through the partition, a sleeve engaging said shank on the rear side of the partition, a pin threaded into said shank, and extending rearwardly and bearing rearwardly against the wall of the chest, said pin being adapted for adjustment to apply stress to said member to hold the partition rigidly in its final position.

7. The combination in a burglarproof chest having a front door and a door opening of a partition having a door, a door opening and a slot for the quick insertion of articles to be stored, the partition being in a plurality of sections to be inserted through the door opening, means for connecting the sections together in assembling the partition, and means accessible for removal only through the door opening in the partition for supporting the partition in the position of the chest to divide it into an inner and outer compartment, 130 said means comprising a member extending forwardly from the partition and engaging supporting means within the chest, said member having a shank extending through the partition, a sleeve engaging said shank on the rear side of the partition, a pin threaded into said shank and extending rearwardly and bearing rearwardly against the wall of the chest, said pin being adapted for adjustment to apply stress to said member to hold the partition rigidly in 135

140 its final position.

8. The combination in a burglarproof chest having a front door and a door opening of a partition having a door, a door opening and a slot for the quick insertion of articles to be stored, the partition being in a plurality of sections to be inserted through the door opening, means for connecting the sections together in assembling the partition, and means accessible for removal only through the door opening in the partition for supporting the partition in the position of the chest to divide it into an inner and outer compartment, said means comprising a member extending forwardly from the partition and engaging supporting means within the chest, said member having a shank extending through the partition, a sleeve engaging said shank on the rear side of the partition, a pin threaded into said shank and extending rearwardly and bearing rearwardly against the wall of the chest, said pin being adapted for adjustment to apply stress to said member to hold the partition rigidly in 145 150

its final position and locking means for securing said pin.

8. In a burglarproof chest having a front door opening, an inner partition having a slot and a door opening therein, means for securing the partition within the chest comprising forwardly and rearwardly projecting members consisting of forwardly projecting struts and rearwardly projecting longitudinally adjustable means, the chest having rigid supporting means for said forwardly and rearwardly projecting members at the front and rear, respectively, the adjustment being accessible through the door opening in the partition.

15 9. In a burglarproof chest having a front door

opening, an inner partition having a slot and a door opening therein, means for securing the partition within the chest comprising forwardly and rearwardly projecting members consisting of forwardly projecting struts and rearwardly projecting longitudinally adjustable means, the chest having rigid supporting means for said forwardly and rearwardly projecting members at the front and rear, respectively, the adjustment being accessible through the door opening in the partition, and means extending through the partition connecting said forwardly and rearwardly projecting members together.
